PROGRAM CHANGE INDICATOR

Roland A. Lynn, Teaneck, N. J., assignor to Radio Corporation of America, a corporation of Delaware

Application February 13, 1943, Serial No. 475,728

9 Claims. (Cl. 250—17)

1

This invention relates to program change indicators and has particularly to do with a method of automatically monitoring the modulated wave of a transmitted radio signal and comparing it with the original wave at the point of origin. The invention also has other uses, as will be apparent to those skilled in the art.

In the field of broadcasting the possibility exists, unfortunately, that the wire channel between a studio and the transmitter might be severed by an act of sabotage, and at the same time an unauthorized program might be substituted to modulate the transmitter's carrier. The substitution of such a program, if of a subversive nature, could easily create a panic. Program circuits between studios and associated transmitters might be subject to such acts of sabotage without the knowledge of anyone in the studio. Furthermore, no dependable means are available at the transmitter whereby a substitute program could be detected, especially if it appeared to be innocuous.

Accordingly, it is an object of my invention to provide a radio program monitoring system including a comparison device by which an alarm may be sounded, or a visual indicator may be actuated, whenever a difference occurs between the modulated waves applied to an outgoing line and such waves brought in for comparison by a radio receiver which is tuned to the associated transmitter.

It is another object of my invention to provide a system of the class described in which an alarm device may be actuated whenever there is a departure from a normal ratio between the volume of the studio output signal and the volume of the incoming monitoring signal from the transmitter. This means, of course, that the alarm will be sounded whenever a pause occurs in one modulated wave without a corresponding pause in the other modulated wave. It means, further, that an increased volume in one wave without a simultaneous increase in volume in the other wave shall likewise be used to actuate the alarm.

According to another object of my invention, means are provided in combination with the aforementioned comparison device for producing a certain limiting action upon the signal energy component which is derived directly from the studio output circuit and which is applied to the comparison device. The purpose of the limiter is to compensate for a limited modulation which is characteristic of the signal as radiated by the transmitter.

In carrying out my invention, I have provided

2

a system which departs from practices of the prior art in the following respects:

I have arranged for my alarm device to respond only to unfavorable comparisons between the volume level of the studio program and that of the same program as received on a monitoring radio. Heretofore, systems have been tried in which the alarm would be subject to failure if the transmitter modulation output continued during the absence of studio output. A failure of the alarm also resulted from the application of a relatively high level substitute signal to the transmitter modulator during a period of low volume output from the studio. Such "one-way" alarm systems are to be avoided in a dependable monitoring system such as I have disclosed herein.

One of the weaknesses of the comparison devices used in the past arose from attempts to control the gain in the amplifiers by half-wave rectification of the signal components. I have found that full-wave rectification is practically essential to a successfully operable device of this character.

My invention will now be described in more detail, reference being made to the accompanying drawing, the sole figure of which represents in diagrammatic form a preferred circuit arrangement.

The terminals 1 are connected in any suitable manner to a studio output circuit on which a modulated audio frequency wave is impressed. The energy is applied across transformer 2 to a load impedance 3 having a center-tap 4 which connects with a center-tap on the secondary of transformer 2. The impedance 3 may be used as a voltage divider, taps from which are connected respectively with the control grids in two discharge tubes 5. These tubes are connected for push-pull amplification. Their cathodes are connected through a milliammeter 6 to a suitable point on a voltage divider 7. By this connection, the normal cathode potential is maintained at a suitable value above ground potential, as indicated at the left end section of the voltage divider 7.

The amplifier tubes 5 are preferably of the pentode type, for the reason that they possess a variable mu characteristic which is of value in obtaining a wide latitude of control action. The screen grids are connected through resistor 52 to junction 16 on the voltage divider 7. Each suppressor grid is connected to its cathode. The anodes are connected to the primary terminals of a transformer 8. This primary has a center-tap to which anode potential is applied from the right hand end of the voltage divider 7. A power

supply unit 9 is used to obtain all the necessary potentials for the different electrodes of tubes 5 and for other tubes as well.

The anodes of tubes 5 are also interconnected by an impedance circuit 10 at the center of which is a connection with the center-tap on the primary of transformer 8. One arm of this impedance circuit is used as a potentiometer for withdrawing a signal voltage component to be used for amplitude limiting. This signal component is impressed through an impedance which includes resistor 11, capacitor 12, and resistor 19, the latter being connected to the voltage divider 7 at point 18. The control grid in a discharge tube 13 responds to this signal potential as applied across resistor 19. This tube is preferably of the duplex-diode-triode type. The triode section includes the cathode, control grid, and main anode 14. The diode section includes two anodes 15 adjacent the cathode. The D. C. potential of the cathode is fixed by its connection to point 17 on potentiometer 7.

The main anode 14 is supplied with a plus D. C. potential from a point 16 on the potentiometer 7, this point being connected to one terminal of a primary winding in transformer 33. The other terminal of this primary is connected directly to the anode 14.

Transformer 33 has a secondary winding, the terminals of which are connected respectively to the two anodes 15. This secondary also has a center-tap which is connected to ground through resistor 22. The control grids in the push-pull amplifier tubes 5 are biased in part by the potential drop across resistor 22.

A D. C. potential for normal grid bias is derived from point 18 on the potentiometer 7 and is impressed upon the control grid of tube 13 through grid leak resistor 19.

From the above description, it will be seen that the triode section of tube 13 is enabled to amplify a signal component, and this amplified component is rectified, causing a negative bias potential to be impressed upon the control grids in tubes 5 in dependence upon the amplitude of the signal itself. Thus excessive peaks of energy are limited and only signals within a limited volume range are fed across the transformer 8. The gain reduction is very rapid. The time constant value of the gain recovery is dependent upon the values of capacitor 21 and the grid leak resistor 22. These values may, for example, be of the order of .25 mfd. and 4 megohms, respectively.

The limiter tube 13 serves a very useful purpose under ordinary circumstances. It operates to rapidly establish a lowered gain characteristic upon the advent of an audio wave form of abnormally high peak value, but does not disturb the established operating bias of the tubes 5 during the presence of signals within a normal range of amplitude variation. The desired degree of the limiting action may be selected by adjustment of the tap on potentiometer 10. In certain cases the limiter tube might be dispensed with and a conventional automatic gain control circuit may be connected to the input circuit of the amplifier tubes 5.

The limited modulation wave output from tubes 5 is fed across transformer 8 to the anodes of a double-diode full-wave rectifier tube 23. A desirable attenuation of the higher audio frequencies is obtained by the use of capacitors 24 which are shunt-connected across the anode leads of tube 23. Grounded by-pass condensers 36 may also be provided for the same purpose.

The common cathode of tube 23 is connected to point A on a balanced bridge circuit consisting of four resistors 25, 26, 27, and 28. Resistors 25 and 26 are preferably made equal to each other. Resistors 27 and 28 may, if desired, be of the order of one megohm each. These values, however, are not critical.

Point C on the bridge circuit is connected to the mid-tap on the secondary of transformer 8. Point D is grounded. Point B on the bridge circuit is diametrically opposed to point A and receives rectified signal potentials from a circuit presently to be described.

Referring now to the lower portion of the circuit diagram, I show input leads 41 to which are applied audio frequency output energy from a monitoring radio receiver. The primary winding of a transformer 42 is connected to the terminals 41. The secondary winding 34 of transformer 42 feeds energy to a load impedance 44 which is preferably composed of a potentiometer having a tap connected to the control grid of an amplifier tube 45. One terminal of the secondary 34 is grounded and is also connected through a cathode resistor 46 to the cathode of tube 45. Resistor 46 is preferably shunted by a capacitor 47.

Although the amplifier tube 45 is shown as a triode, tubes of other types may be used if desired. Anode potential is supplied to the tube 45 through the primary winding of a transformer 48 from junction point 16 on the potentiometer 7.

Transformer 48 is used for the purpose of coupling the output from tube 45 to the anode circuit of a double-diode full-wave rectifier tube 43. The secondary winding of transformer 48 is center-tapped and is connected to point C on the above described bridge circuit. The terminals of the secondary of the transformer 48 are connected respectively to the anodes in tube 43. The common cathode of tube 43 is connected to point B on the bridge circuit and also to a control grid in a discharge tube 49 which is used as a control value in a relay circuit.

Two discharge tubes 49 and 50 are suitably connected to be controlled by differences of potential in different arms of the bridge circuit so that either one of two relays 52 and 53 may be de-energized whenever an unbalance of potentials occurs in the bridge circuit. Normally the relays 52 and 53 are energized by a conductive state in the two tubes 49 and 50. The relays 52 and 53 are disposed in the anode circuits of tubes 49 and 50 respectively. These anode circuits also preferably include milliammeters 51 for convenience in observing the operation of the system.

The power supply unit 9 furnishes current for operation of the relays 52 and 53 through the space paths of tubes 49 and 50 respectively. The relay circuits are completed through the cathodes of tubes 49 and 50, through the two arms of a potentiometer 54, and through series resistors 55 and 56 to ground. Resistor 56 is preferably made adjustable and the tap on potentiometer 54 may also be adjusted for balancing the amplitudes of the currents through tubes 49 and 50.

In order to facilitate the starting up or resetting of the apparatus after an alarm and particularly in order to energize relays 52 and 53, it is advantageous to momentarily short-circuit at least a part of the impedance of elements 55 and 56. This is accomplished by actuating a key (not shown) which closes contacts 57 and

thereby places resistor 58 of relatively low resistance value in shunt with resistors 55 and 56. This operation enables the tubes 49 and 50 to draw more than a normal flow of current and thus to energize the relays 52 and 53. Under normal operating conditions, the current flow through tubes 49 and 50 is sufficient to hold up the armatures 60 and 70, but may be insufficient to attract them across their gaps.

Any one or more alarm devices may be actuated whenever either of the relays 52 and 53 is sufficiently de-energized by at least partially blocking the associated tube 49 or 50 respectively. The armature 60 of relay 52 is associated with a back contact 61, the latter being connected to one terminal of an energy source 63. The other terminal of this source is connected through a switch 64 to common return circuit 65 for all of the alarm devices.

Illustratively, four different types of alarm device are indicated in the diagram. These are lamps 66 and 76, buzzers 67 and 77, annunciators 68 and 78, and a monitoring speaker 40. The circuits for the different alarm indicators 66, 67, and 68 are preferably in parallel. The indicator units 76, 77, and 78 are also connected in parallel. Although the individual indicator units may be separately cut in and out of service by individual switches, it is a simpler matter to provide one switch 64 for opening them all at once after the alarm has been noted.

Relay 53 has an armature 70 associated with a back contact 71 for controlling the parallel connected circuits through indicator lamp 76, buzzer 77, and annunciator 78. These alarm circuits are likewise actuated whenever the armature 70 is released by relay 53, that is to say, when the tube 50 becomes sufficiently blocked.

The winding of a relay 37 may, if desired, be inserted between the common leads 38 and 65 of the alarm indicator circuits. Relay 37 has contacts which are closeable to short-circuit an attenuating resistor 39 in the voice circuit of a monitoring loud speaker 40. Thus the relatively low-level input to the speaker 40 may be raised to a high level whenever either of the alarm relays 52, 53 releases.

The operation of my program change indicator is further explained as follows:

The voltage developed across resistor 25 in the bridge circuit is dependent upon the amplitude of the signal component which is rectified by the tube 23. Likewise, the voltage developed across resistor 26 is attributable to the amplitude of the signal component rectified by tube 43. When the voltage drop in resistor 25 equals that in resistor 26, then equal biases are applied to the grids of tubes 49 and 50 and these biases are of such value that emission takes place in both tubes, and they normally draw sufficient current to maintain the relays 52 and 53 in an energized state. Under this balanced condition, regardless of the signal amplitudes, points A and B are both at substantially ground potential.

When the rectified signal potential in tube 23 exceeds that in tube 43, then the difference between the potential drop across resistor 25 and across resistor 26 is such that point A on the bridge circuit is rendered positive with respect to ground and point B is rendered negative. This is true because the values of resistors 27 and 28 are equal and point D is grounded. Therefore, the ground potential applied to point D is one with reference to which the voltages of points A and B move equally in opposite directions, the extent

of such movement being dependent upon the degree of unbalance between the rectification components from tubes 23 and 43.

Whenever point A is driven sufficiently negative with respect to ground so that the impedance through the space path in tube 50 becomes too great to permit relay 53 to hold up its armature 70, this armature is released and causes the alarm indication to be made in such manner as to show an abnormal output from the transmitter with reference to the studio output. Also when point B on the bridge circuit is rendered sufficiently negative with respect to ground, then the impedance of tube 49 becomes too great to allow armature 60 on the relay 52 to be held up. The alarm indication is then made so as to indicate a failure on the transmitter side of the comparison device.

If the alarm circuits which include pilot lamp 76, buzzer 77, and annunciator 78 are actuated, then it is known that an abnormal condition has occurred in which the output from the transmitter cannot be accounted for as originating at the studio. The reverse condition is indicated by the actuation of pilot lamp 66, buzzer 67, and annunciator 68 when the tube 49 becomes at least partially blocked and relay 52 de-energizes. The amplitude of the output from the loud speaker 40 will be greatly increased upon setting off either side of the alarm circuit, provided there is any signal at all which the monitoring radio receiver can pick up.

For the purpose of smoothing the rectified potential output from tubes 23 and 43, I preferably place a delay circuit in shunt with resistors 25 and 26. This delay circuit includes capacitors 29 and resistors 30. The junction between the two capacitors is connected to point C on the bridge circuit and also to the anode circuits of the rectifier tubes 23 and 43.

It will be seen from the above description that my automatic program change indicator is of value not only in detecting subversive acts which would interfere with the proper operation of a broadcasting system, but it is also of value for giving an alarm whenever an abnormal transmission condition occurs. The loss of normal established levels due to partial or complete failure of any of the equipment in the paths between the points of origin and reception of the transmitted signal makes itself evident in the operation of the alarm system. Failure may occur in the wire lines, at the equipment of the transmitter, at the transmitter itself, the transmitter antenna, the propagation space path, or in the radio receiver. Abnormally high levels of signal reception as well as abnormally low levels on a comparative basis will result in giving an alarm. Various alarm devices, not only such as shown, but of other types as well may be placed at any convenient points and those which are parallel connected with each other may be disposed at different points remote from one another, if desired.

Various modifications of my invention will, doubtless, suggest themselves to those skilled in the art in view of the foregoing description. Such modifications would, however, be comprehended within the spirit and scope of the invention.

I claim:

1. A program change indicator system for use in connection with a broadcast studio output circuit and with a monitoring receiver, said system comprising separate full-wave rectifiers, one

being coupled to said studio output circuit and the other being coupled to the output side of said receiver, means including a four-arm bridge circuit for comparing the instantaneous energy components delivered by said rectifiers, one arm of said bridge circuit being in series with the rectifier which delivers the studio energy component, a second arm of said bridge circuit being in series with the rectifier which delivers the monitoring receiver energy component, the third and fourth arms being each grounded at one end thereof and being connected at the other ends to the first and second arms at the respective junctions of the latter with the cathode electrodes of said rectifiers, conductive circuits interconnecting the anode electrodes of both rectifiers with the junction between the first and second bridge arms, a pair of relays each having its winding in circuit with the space path of an individual discharge tube, means for controlling said tubes in opposite senses in response to unequal potentials developed across the first and second bridge arms, and indicating means selectively actuatable by said relays.

2. In a program change indicator which compares audio-frequency potentials from two different sources normally possessing the same wave envelope, the method of actuating a relay-controlled alarm upon the reception of unlike wave envelopes from said sources, said method comprising separately amplifying and rectifying a full-wave signal component from each source, producing two currents of substantially equal value in response to the rectification of said signal components so long as they follow the same wave envelope, causing the amplitudes of said currents to vary in opposite senses in response to the reception of unlike wave envelopes, causing a limiting action to be produced with respect to the amplification gain factor which is applied to the signal components from at least one of said sources, and causing said alarm to be actuated by a relay circuit closure which takes place when the disparity between said current amplitudes reaches a predetermined value.

3. In a program change indicator which compares audio-frequency potentials from two different sources normally possessing the same wave envelope, the method of actuating a relay-controlled alarm upon the reception of unlike wave envelopes from said sources, said method comprising separately amplifying and rectifying a full-wave signal component from each source, producing two voltages of substantially equal value in response to the rectification of said signal components so long as they follow the same wave envelope, causing the values of said voltages to vary in opposite senses in response to the reception of unlike wave envelopes, causing a limiting action to be produced with respect to the amplification gain factor which is applied to the signal components from at least one of said sources, and causing said alarm to be actuated by a relay circuit closure which takes place when the disparity between said voltages reaches a predetermined value.

4. An alarm circuit arrangement comprising two full-wave rectifiers each transformer-coupled to a different source of audio frequency wave energy, the two said sources normally possessing the same wave envelope, a first, a second, a third and a fourth impedance constituting the four arms of a Wheatstone bridge, a connection from the cathode electrodes of one said rectifier

to the junction between the first and third impedances, a connection from the cathode electrodes of the other said rectifier to the junction between the second and fourth impedances, circuit means connected to the junction between the first and second impedances and branched to the anode electrodes of both rectifiers for producing potentials across the first and second impedances in accordance with the relative amplitudes of the wave energy from the different sources, a ground connection to the junction between the third and fourth impedances, a pair of electronic tubes each having an input circuit connected between its ground-connected cathode and its control grid and having a load in its output circuit, a connection from the control grid of one tube to the junction between the first and third impedances, and another connection from the control grid of the other tube to the junction between the second and fourth impedances, whereby the unbalancing of potentials across the first and second impedances varies the output of said tubes in opposite senses.

5. A circuit arrangement in accordance with claim 4 in which each said load is constituted as the winding of a relay, and said circuit arrangement includes an alarm indicator operable upon de-energization of one of said relays, and a second alarm indicator operable upon de-energization of the other of said relays.

6. A circuit arrangement in accordance with claim 4 in which each said load is constituted as the winding of a relay, and said circuit arrangement includes a plurality of alarm indicators operable upon release of a relay armature, certain of said indicators being individual to each relay and at least one indicator being common to both relays.

7. A circuit arrangement in accordance with claim 4 in which each said load is in circuit with the winding of a common relay and said circuit arrangement includes a load speaker the voice circuit of which includes an attenuating impedance, and means operable by said relay for short-circuiting said attenuating impedance thereby to increase the output of sound from said loud speaker.

8. In a system for comparing the modulation envelopes in two trains of signals normally having a common source, one of said trains being applied to and derived from a space path of radio propagation and the other of said trains being applied to and derived from an essentially metallic circuit, separate means for amplifying and rectifying the signal energy in each of said trains, a four-arm bridge circuit arranged to be fed with rectified energy components from said separate means, and an alarm circuit responsive to a condition of energy unbalance in corresponding arms of said bridge in the event that the characteristics of said modulation envelopes in the two said trains differ by a predetermined amount.

9. A system according to claim 8 and including two indicators operatively connected to said alarm circuit, one of said indicators being responsive to an unbalance of potentials in said bridge circuit which results from an abnormally high energy content of the signal train derived from radio propagation, and the other of said indicators being responsive to an unbalance of potentials in the opposite sense.
